LIGHT PROJECTION APPARATUS

Roland E. Gunther, Newark, N. J.

Application August 19, 1950, Serial No. 180,333

2 Claims. (Cl. 313—113)

1

This invention relates to a light projecting apparatus, and more particularly to an apparatus for collecting light rays emanating from a source, and so directing them that there results a well-defined separation between illuminated and non-illuminated areas. The invention is particularly adaptable for use as a vehicle headlight system.

It is an object of the present invention to provide a light projecting apparatus for vehicles, wherein adequate illumination is provided for driving while glare in the eyes of other operators is eliminated.

It is a further object to provide an improved arrangement of filament and reflectors for directing light in the manner described.

The objects and advantages of this invention will become more apparent in the following description and drawing.

In the drawing constituting a part of this application, and in which like numerals refer to corresponding parts throughout:

Fig. 1 is a side view in section of the apparatus, showing in addition to the parts that would be seen in this section, some of the light rays emitted from the source and the manner in which they are directed by the device.

Fig. 2 is the same view as in Fig. 1, but showing a different group of light rays.

Fig. 3 is a top view in section of the apparatus.

In the drawing, and distinguished by reference numerals, are shown, in Fig. 1 a parabolic plane reflector 1, and in the focal point of parabolic plane reflector 1, a filament 2 in cross section. The axis of the parabola to which reflector 1 conforms is indicated by a line marked *a*. Positioned above and extending forwardly from the upper edge of parabolic plane reflector 1 is a flat plane reflector 2. Flat plane reflector 3 is parallel to the axis *a* of parabolic plane reflector 1. Parabolic plane reflector 1 and top flat plane reflector 3 are so inclined that a horizontal line drawn through the focus of parabolic plane reflector 1, as illustrated by the broken line marked *b*, just touches the end of flat plane reflector 3 away from parabolic reflector 1. Positioned opposite parabolic plane reflector 1 and with its upper edge adjoining the forward edge of top plane reflector 3 is a transparent member 4. Between the lower edge of transparent member 4 and the lower edge of parabolic plane reflector 1, and joined to both is a non-reflecting panel 5. Shown also in Fig. 1 are two light rays 6 and 7 representative of those rays emitted from filament 2 which are given direction by means of reflection from the parabolic plane reflector 1.

2

Shown in Fig. 2 of the drawing are the same parts as in Fig. 1 and in place of the group of light rays mentioned above, in Fig. 2 are shown a light ray 8 representative of the rays which, coming directly from the filament 2, strike the top flat plane reflector 3 and are directed then through the transparent member 4; and a light ray 9 representing those rays which when emitted from the filament 2 pass in the space between top flat plane reflector 3 and non-reflective panel 5 without touching either, to leave the device via transparent member 4.

In Fig. 3 is shown a top view of the device in section, and herein the parabolic plane reflector 1 has a straight section. Filament 2 is also shown, and namely as a straight line element horizontally placed, and attached to electrical leads 10 and 11 to permit the conduction of electricity to the filament 2. The inner reflective surface of parabolic plane reflector 1 is parallel to filament 2. Shown in this view are sides 12 and 13 of the device through which pass the leads 10 and 11, and which, together with the transparent member 4 shown here and reflector 1, as well as top plane reflector 3 and non-reflective panel 5 previously shown, all combine to form a continuous enclosure.

The parts of the device having been identified, there follows a description of the characteristics and features, with appropriate references to the drawings, to show how the device directs the rays of light produced in it.

When the device is installed in a vehicle and positioned with respect to the horizontal as described, so that the focal point of the parabolic plane reflector 1 and the forward end of flat plane reflector 3 are on the same level, and a suitable current is passed through the filament 2 light will be emitted in all directions therefrom. Those rays striking the parabolic surface of reflector 1 are all reflected in such a manner that they proceed parallel to the axis of the parabola. The axis being sloped downwardly with respect to the horizontal, the rays 6 and 7 will have the same downward slope, as will all others reflected from the parabolic reflector. Since the focal point, in which the filament 2 is located, is on the same level as the forward end of top plane reflector 3 the slope of reflector 3 will be given by the ratio: one half the height of parabolic plane reflector 1 to the length of top flat reflector 3. The points of measurement for both of these dimensions are indicated in Fig. 1.

Headlights on automobiles are conventionally placed at a height of approximately 36 inches from the ground. This usage would be adhered

to in the application of this invention, since higher placement puts the headlights on too nearly the same level as the eyes of other drivers, and when placed lower the light beams would shine more along the ground than at it.

With the headlights under discussion placed at conventional height from the ground, and the closest point usually visible to the driver in front of his vehicle being in the range of 30 feet, the majority of the light rays must drop less than three feet in thirty feet of longitudinal travel for efficient operation. This means that the ratio of one half the height of parabolic plane reflector 1 to length of flat plane reflector 3 would be at least 1:10, or better put the ratio of parabolic reflector height to top reflector length would be at least 1:5. The preferred ratio, however, is much higher since at common driving speeds it is necessary to provide illumination much further ahead of the vehicle. For the rays to be directed forwardly to a distance of 240 feet, for instance, the ratio of parabolic plane reflector height to top flat plane reflector length is 1:40 and it is in ranges of this and greater magnitudes of ratios that the device is used. The upper limit of ratios is set only by design restrictions imposed by such factors as maximum space actually available for the top reflector, and minimum distances allowable between an incandescent filament and a reflecting surface without the latter being impaired by the heat from the filament. The unique feature found in this invention which is embodied in the uncoiled filament extended in a straight line along the inner surface of the parabolic plane reflector, permits the latter distance to be reduced much more than would be possible in previous practice, since it spreads the heat along a line instead of concentrating it at a point as is usually done in paraboloid reflecting devices.

Of the rays which are not directed by reflection from the parabolic plane reflector, there are those as shown in Fig. 2, which, like light ray 8 move in such a manner as to strike and be reflected from top reflector 3. Upon reflection they are directed more downwardly than the slope of reflector 3, and together with light rays that move initially more downwardly, such as typified by ray 9 provide illumination in the area between the zone of maximum illumination created by the parabolic reflector, and the vehicle. A small portion of the light emitted will be in the angle between lines *h* and *a* of Fig. 1 and directed more upwardly than the majority of the rays. The highest ray that can leave the device, travels along line *h* after being emitted from the filament 2. Line *h* being horizontal, this means that no rays project above the horizontal, and the device being below the eye-level of other operators, this device cannot produce glare.

Previously used vehicle headlight equipment caused glare from two sources. One was the inefficiency of reflection from the paraboloid reflectors used prior to this invention, due to the fact that a point source of light would be needed for full control of the reflected light, and the actual source could not be made small enough. The present device, as may be seen from the side sectional views, presents to the parabolic section the cross section of the filament, which is practically a point source for the light. The other, and main disadvantage of previous equipment overcome by

the present invention, is the fact that in the past the source of light, that is, the incandescent filament, was fully visible to the opposing motorist, and with the high candle-power units in common use, the combination of inefficient reflective direction and unshielded direct view of the filament produced a blinding glare, while in the present device neither source of glare is present. Further, with the present device there is no need to have a "high beam" and a "low beam" as in devices used previously. The high beam being the normal and glareless beam, motorists are no longer put at the mercy of each other to change to a considerate low beam when approaching one another, nor is it any longer necessary to forfeit the ability to see ahead of the vehicle in consideration of the other motorist by switching to a less efficient illumination.

In the execution of the device herein described, the reflectors are preferably constructed as first surface mirrors to enable them to reflect efficiently at the very small angles of incidence involved in much of their function.

I claim:

1. In an apparatus for the projection of light, the combination with a parabolic plane reflector, and a straight line horizontal filament located in the focus of said parabolic plane reflector, of a flat plane reflector abutting against the upper edge of said parabolic plane reflector and extending forwardly therefrom in a direction parallel to the axis of said parabolic plane reflector, said parabolic plane reflector and adjoining said flat plane reflector being inclined forwardly downward from the horizontal in such a manner that the end away from said parabolic plane reflector of said flat plane reflector is on the same level as the focus of said parabolic plane reflector, and a transparent member positioned opposite said parabolic plane reflector and adjoining and extending downwardly from the forwardmost edge of said flat plane reflector, and a non-reflective panel extending from the bottom edge of said parabolic plane reflector to the bottom edge of said transparent member, and side panels placed against and joined to the left and right edges respectively of the system formed by said parabolic plane reflector, said flat plane reflector, said transparent member and said non-reflective panel, so constituting a continuous enclosure.

2. In an apparatus for the projection of light, the combination as claimed and described in claim 1, wherein the relative dimensions of said parabolic plane reflector and said flat plane reflector are such that the length of said flat plane reflector is more than ten times the height of said parabolic plane reflector.

ROLAND E. GUNTHER.
